(57) CLAIM

The ornamental design for a toilet brush holder, as shown and described.

DESCRIPTION

FIG. 1 is a front perspective view of a toilet brush holder, showing my design.

FIG. 2 is a front elevation view thereof.

FIG. 3 is a rear elevation view thereof.

FIG. 4 is a right side elevation view thereof.

FIG. 5 is a left side elevation view thereof.

FIG. 6 is a top plan view thereof.

FIG. 7 is a bottom plan view thereof; and,

FIG. 8 is a perspective view of the toilet brush holder of FIG. 1 wherein a drawer of the toilet brush holder is opened.

The broken lines shown in the figures represent portions of the toilet brush holder that form no part of the claimed design.
